UNITED STATES PATENT OFFICE.

GEORGE M. TROUP, OF DAYTON, OHIO, ASSIGNOR, BY MESNE ASSIGNMENTS, TO FRIGID-AIRE CORPORATION, A CORPORATION OF DELAWARE.

REFRIGERATION APPARATUS.

Application filed October 17, 1927. Serial No. 226,536.

The present invention relates to improvements in refrigerating apparatus of the mechanically operated type in which a compressor-expander type of circuit is used for effecting refrigeration in a cooling unit.

It is an object of the invention to provide an improved means for operating a plurality of such units simultaneously with one compressor and for permitting the operation of 10 said units at selective temperatures.

It is another object of the invention to provide improved means for controlling the supply of refrigerant to each unit independently of the others in response to the temperature there prevailing.

It is a further object of the invention to provide a common return conduit for the refrigerant of all of the units of a refrigerating system in which the flow of refrigerant is 20 controlled by the pressure within the units and to provide means responsive to the pressure in such conduit for controlling the refrigerant circulating mechanism.

Further objects and advantages of the 25 present invention will be apparent from the following description, reference being had to the accompanying drawing, wherein a preferred form of the present invention is clearly shown.

In the drawings:

Fig. 1 shows a diagrammatic view of the improved refrigerating system of the invention;

Fig. 2 is a view in cross section of a control 35 device used in the system for governing the operation of the units; and

Fig. 3 shows an expansion valve used in the system for producing the refrigeration in the various units.

In the mechanical type refrigerator the 40 flow of refrigerant is preferably effected by means of a compressor-expander type of mechanism wherein a suitable refrigerant is forced by a pumping mechanism through an 45 expansion valve or the like, into a loop of pipes or the like, generally termed an evaporator, which latter is termed the cooling unit or refrigerating element.

When a plurality of such units or elements 50 are operated from one compressor, it may be desirable to control the operating temperatures in the individual units in such a manner that it will be possible to control the

temperatures of the units independently of one another, for example it may be desirable 55 to maintain one unit at one temperature and another unit at a different temperature.

In accordance with the present invention means are provided for controlling the flow of refrigerant to each unit in response to the 60 condition of the unit and more particularly to the temperature of the unit. A common return circuit is provided for all of the units and means are associated with such circuit for controlling the refrigerant circulating 65 mechanism.

Referring in detail to the drawings, the refrigerating system to which the invention is applied by way of illustration comprises a compressor 10 driven by a motor 11 through 70 a belt 12. The compressor forces gaseous refrigerant through pipe 13 into the condenser 14 where it is cooled and from which it passes by way of pipe branches 15 and 16 to the expansion valves 17 and 18 which allow it to 75 issue under pressure through narrow orifices into the evaporators 19 and 20. These evaporators are disposed preferably in insulated cabinets or compartments diagrammatically indicated by 21 and 22 respectively. A common return conduit 23 is provided for both cooling units and serves to return the refrigerating medium to the compressor.

The operation of each expansion valve is controlled by means of devices 24 and 25 80 which are responsive to the temperatures prevailing in the compartments 21, 22 cooled by the evaporators 19, 20. Each of these temperature responsive devices may be set if desired, for different temperatures so that the 85 chamber 21 for example, may be maintained at a different temperature from chamber 22.

Fig. 2 shows one of the temperature responsive devices 24 and 25 in detail. The device comprises essentially a metallic casing 26 90 provided with means such as threads 46 for attachment to the interior of compartments 21 and 22 and containing a valve 27 bearing against valve seat 28 for controlling or obstructing the flow of fluid between passages 29 and 30. The head of valve 27 is carried by a flexible body 31 such as a metallic bellows preferably of the type known in the trade as a sylphon. This body may be filled 95 with a fluid readily responsive to changes in temperature. It is obvious that the dilation 100

and contraction of the bellows 31 will operate the valve head 27 and hence control the flow of fluid from passage 29 through passage 30. The valve may be calibrated by screwing the head 27 more or less into the threaded bushing 32 on the head of the sylphon.

The expansion valve shown in Fig. 3 as an illustrative executional example of one portion of the apparatus of the invention may be 10 of any suitable type.

In the valve shown, liquid refrigerant enters at 33 and passes into the chamber 34 whence it leaves by pipe connection 35, its passage from 33 to 35 being controlled by a 15 needle valve 36. The operation of needle valve 36 is controlled by a diaphragm 37. The needle valve is carried on a yoke 38 shown in cross section which is attached to the center of the diaphragm and which latter 20 in turn is secured at its edges to the casing and thus forms one wall of the chamber. A rod 39 is attached to the diaphragm and to the yoke so as to form a rigid structure with the yoke and the needle valve. This rod is 25 urged to the right as shown in the drawing to close the valve 36 through intermediary of a spring 40 which is compressed between an adjustable nut 41 and shoulder 42. The chamber 43 and therefore the side of the diaphragm facing it is exposed to the influence 30 of atmospheric air and the diaphragm is moved to the left to open the valve against the force of the spring 40 whenever a reduction of pressure occurs in the chamber 34.

35 The operation of the system is as follows: The expansion valve shown in detail in Fig. 3 and diagrammatically indicated by 17 and 18 in Fig. 1 is arranged to maintain a constant pressure in the evaporator or cooling unit 19, one of the several units being selected for discussion of the operating principle. The flow of fluid to the expansion valve 18 is controlled by the sylphon operated temperature-responsive device shown in detail in 40 Fig. 2 and diagrammatically indicated by 24 in Fig. 1. This valve is placed in the compartment 21 so as to be directly affected by the temperature conditions there prevailing.

45 As the temperature of the compartment increases the temperature and likewise the pressure in the evaporator 19 will increase and by the time that this pressure attains a predetermined value the bellows 45 will have expanded sufficiently to actuate the switch to close the motor circuit thus starting the compressing cycle. The setting or calibration of control valve 24 is such that it will open prior to the starting of the motor. The flow of refrigerant to the evaporator is controlled 50 primarily by the expansion valve 18. However, when a predetermined low temperature is attained in the chamber 21 valve 24 will operate to obstruct the flow of refrigerant to the cooling unit 19. Although chamber 21 55 may be cooled sufficiently so that 24 is closed,

there may still exist a demand for refrigeration in compartment 22 so that the compressor will continue to operate to withdraw refrigerant from the cooling unit 20, and when the temperature of compartment 22 attains a predetermined selected low value the valve 25 will close to obstruct the flow of refrigerant to the cooling unit 20. After all of the control devices 25 and 24 have operated to obstruct the flow of refrigerant to the re- 70 spective units the pressure within the units and in the pipe 23 will decrease quickly and this sudden decrease in pressure will actuate the switch 44 through the bellows 45 to interrupt the motor circuit. It is of course understood that the pressure at which the switch 44 operates to stop the motor is considerably lower than the normal operating pressures within the cooling units. 75

The system shown therefore provides a 80 means for operating a plurality of separate refrigerating elements simultaneously from one refrigerant circulating means with provision for operating each unit at a selective temperature, and controlling the apparatus by means of one switch operated by low pressure prevailing in a return conduit common to all of the refrigerating elements. 85

While the form of embodiment of the invention as herein disclosed, constitutes a preferred form, it is to be understood that other forms might be adopted, all coming within the scope of the claims which follow. 90

What is claimed is as follows:

1. Refrigerating apparatus including in combination a refrigerating element, means for circulating a refrigerating medium through said refrigerating element, means responsive to the pressure of the refrigerating medium in the element for controlling the supply of medium thereto and means responsive to the temperature of said element for controlling the supply of refrigerating medium thereto and means responsive to the pressure within the element for controlling the circulating means. 100

2. Refrigerating apparatus including an evaporator having a refrigerant supply conduit and a refrigerant exhaust conduit, a circulating device for supplying refrigerant to and withdrawing refrigerant from said evaporator, a valve in the refrigerant supply conduit for controlling the flow of refrigerant thereto in response to pressure within said evaporator, a second valve in the refrigerant supply conduit for controlling the flow of refrigerant thereto in response to the temperature surrounding said evaporator, and means for controlling said circulating means in response to the pressure in said exhaust conduit. 115

3. Refrigerating apparatus comprising a plurality of evaporators having individual refrigerant supply conduits and a common refrigerant exhaust conduit, a refrigerant 120

circulating device for supplying refrigerant to and withdrawing refrigerant from said evaporators, means in each refrigerant supply conduit for controlling the flow of refrigerant thereto in response to the pressure in the associated evaporator, means in each refrigerant supply conduit for controlling the flow of refrigerant thereto in response

to the thermal condition of said associated evaporator, and means responsive to the pressure in said common exhaust conduit for controlling the refrigerant circulating means.

10 In testimony whereof I hereto affixed my signature.

GEORGE M. TROUP.
